UNITED STATES PATENT OFFICE.

FRANK MOSSBERG, OF PAWTUCKET, RHODE ISLAND.

TWIST-DRILL-GRINDING ATTACHMENT.

SPECIFICATION forming part of Letters Patent No. 389,095, dated September 4, 1888.

Application filed January 17, 1887. Serial No. 224,632. (No model.)

To all whom it may concern:

Be it known that I, FRANK MOSSBERG, of Pawtucket, in the county of Providence, in the State of Rhode Island, have invented a certain new and useful Improvement in Twist-Drill-Grinding Attachments; and I declare the following to be a specification thereof, reference being had to the accompanying drawings.

10 Like letters indicate like parts.

Figure 1 is a side elevation of my improved grinding attachment for twist-drills. Fig. 2 is a top plan of the same. Fig. 3 shows the same, partly in elevation and cross-vertical section, on the line x of Fig. 2. Fig. 4 is an end view in elevation, as seen from the left-hand end of Fig. 2. Fig. 5 shows a top plan of my twist-drill-grinding attachments mounted upon an emery-wheel grinding-machine. Fig. 15 15 shows, respectively, in rear end elevation, side elevation, and top plan, the gage for adjusting the drill in the grinding position. Fig. 7 is a side elevation of the supplemental drill-holding device. Fig. 8 is a cross section on line x' of Fig. 10. Fig. 9 is an end view of the said supplemental drill-holder. Fig. 10 is a top plan of the same. Fig. 11 is a side elevation of the spring in the same. Fig. 12 illustrates in top plan the position of the same 20 when in use. Fig. 13 is a cross-section on line x'' of Fig. 15. Fig. 14 is a rear elevation of the head-piece and some of its connected parts. Fig. 15 is a cross-section on line x'' of Fig. 14.

My invention relates to attachments for 35 grinding twist-drills upon emery-wheels; and it consists of certain improvements in the details of the machine described in my application for Letters Patent of the United States, Serial No. 215,503, now pending, as well as of 40 additional devices in connection therewith for the more accurate and convenient manipulation of the drill while in process of grinding its lips and point, as hereinafter particularly described, and specifically pointed out in the 45 claims.

In Fig. 5 I show the relative positions and attachment of my improved device and the several parts thereof as applied and used upon an emery-wheel grinder. The emery-wheels 50 A A' are mounted upon a main shaft, B, which is supported within the bearings C. The pulley D is also mounted upon the shaft B and

revolves the shaft and wheels by a belt which communicates the power. Two longitudinally-slotted shelf-pieces, E E', project from the bed 55 of the machine to the front. Thus far I have described a common emery-wheel grinding-machine, to which my grinding devices are attached.

The base F has a T-shaped slot, Fig. 1, into 60 which enters the head and shank of the clamping-bolt G, by which said base F is adjustable upon and fastened to the slotted shelf-piece E of the emery-wheel grinding-machine. A socket-piece, H, integral with the base F, extends upward and has a central bore and open lips, a, Figs. 1, 3. The standard I enters the socket-piece H and is supported thereby and has a horizontal rotary motion therein. When turned to the desired position, the standard I is fastened by means of the set-screw b, which, passing through the lips a, draws them together and binds the socket to the standard. The head-piece J (shown in Figs. 14 and 15) is integral with the standard I. It has a vertical 70 groove, c, in which a block, K, is adjustable by means of a longitudinal slot, as seen at d, and a stop screw-clamp, e. By loosening the screw e the block K may be placed in any desired position in the groove c, and then be 75 held securely in such position by tightening the screw e again.

On the side of the head-piece J, opposite to the groove c, I put a beveled block, L, Figs. 3, 12, 13, 15, and hold it to the head-piece J 80 by the screw f, whose inner end is square and flush with the bottom of the groove c.

The body-plate M, Figs. 2, 3, 12, 13, has a dovetailed channel for the reception of the beveled block L, and a gib, g, with the screw 90 b, takes up the wear of the same. A fixed clamp, N, is integral with the body-plate M, and has a horizontal V-shaped groove or channel throughout its length, Figs. 3, 13. Two fixed pins, O, extend from the clamp N toward the front and support the movable clamp N', which is mounted thereon by suitable bores, through which the pins O pass. The clamp N' has a V-shaped groove on its inner surface, Figs. 3, 13. A screw clamping-bolt, P, has a 95 right-handed screw-thread, i, at its end and a left-handed screw-thread, j, on its shank, midway to the head. The clamps N N' have female screw-threads to correspond. By turn-

ing the screw P these reversely-turned screw-threads give a double action, which cause the clamp N' to rapidly approach to or separate from each other to hold in place and grip the 5 drill Q , Figs. 2, 3.

The main bar R is connected with the clamping-block N . It has on its front side a longitudinal groove, k , Figs. 1, 3, in which a key-piece, l , fits and slides, Fig. 4.

10 The chuck-block S has a channel, Fig. 4, by means of which and the key-piece l it is confined to a direct horizontal movement along the main bar R . A thumb-screw, T , passing through a boss on the side of the chuck holds 15 the chuck S in its adjusted position on the main bar R . The chuck S has an upright drill-stop, m , and two laterally-projecting horns, n n' .

10 A feed bracket, U , Figs. 1, 2, 4, is fastened 20 to the under surface of the main bar R . It has two lugs, o o' , through which the feed-screw V passes. A sliding nut-block, W , is mounted and travels on the feed-screw V . The screw V has a disk or wheel, p , on whose rim 25 is an index. An indicator or finger, q , extending from the lug o , lies over the rim to mark the degree of the turning of the screw.

The nut W has a stud-screw threaded at its 30 end. The connecting-rod X has an eye by which it is fitted upon said stud, and a nut, Y , secures it in place. The connecting-rod X is pivoted to the block K by the screw-bolt Z .

The drill-holder A^2 , Figs. 2, 4, has a central bore or opening and a stem, through which a 35 thumb screw, B^2 , passes. It also has a side rib, r , of such size and shape that when it lies upon the upper surface of the horns n n' of the chuck S alternately the holder describes (in turning the drill Q) an arc of one hundred and 40 eighty degrees. The screw B presses against the drill, and the holder is thus held firmly upon it to turn it as desired. A lever, C^2 , turning on the screw s , is mounted upon the end of the head-piece J . At its lower end it 45 has two steps, t t' . A guide, D^2 , Figs. 2, 3, 5, 6, 12, consists of a spring-stem, u , at the smaller end of which it is fastened to the clamp N by the screw v . The plate of the guide D^2 has its lower edge beveled. (See Fig. 6.)

50 Figs. 7 to 13, inclusive, illustrate a supplemental drill-holder, which is used to hold drills which are of too small a size to be properly gripped by the clamps N N' . It consists of two clamping-bars, E^2 E^3 , connected at each 55 end by cross-plates w , Fig. 12, having a central hexagonal opening and secured to the upper bar, E^2 , by the screw y . The cross-plate is inserted in a groove made in the end of the upper bar, E^2 , and slides in a similar groove 60 in the end of the lower bar, E^3 . The connection of these parts is fully shown in Figs. 10, 12, and 13. The clamping-bars E^2 E^3 are each longitudinally channeled by a V -shaped groove, and in a narrow groove on each side 65 of said V -shaped channel a U -shaped spring, z , is mounted by means of pins a^2 . These springs normally bring the two bars E^2 E^3 of

the clamp together. A handle, b^2 , projects at one end of the clamping-bar E^2 and has a fixed stop pin, c^2 .

70 Operation: To grind the lips of the drill, I first adjust the drill-grinding attachment, Fig. 1, to the slotted shelf E of the grinder and secure it in the required position by the bolt G . I then swing the grinding attachment into the 75 proper angular position relative to the grinding-wheel, Fig. 5, by rotating the standard I in the socket H and confining it in place by the set-screw b . I then insert the drill through the holder A^2 and between the clamps N N' , 80 for which purpose I open the said clamps by unscrewing the clamp-screw P , which causes the movable clamp N' to move along the pins O outwardly. The drill Q which is to be ground is laid in the V -shaped channels of 85 said clamps loosely with one hand, and with the other hand I press downward the gage D^2 . I then determine the proper location of the drill Q in the machine by bringing into contact with the beveled edge of said gage that 90 corner of the drill-lip which is formed by one of the extreme edges of the flute with the extreme outer edge of one of the lips. This location or adjustment of the drill in place determines the proper line in which to advance 95 the drill to the grinding-wheel, so as to present the lip in the desired relation to the grinder. This location of the drill in the clamps having been determined in this manner, I relieve the gage from the pressure of my 100 hand, and the gage rises by the resilience of its spring, to its former elevated position, where it is clear of the drill. I now advance the drill in a straight line without turning until the lip which is to be ground comes 105 against the grinding-wheel. I then slide the chuck S along the main bar R until its drill-stop m bears against the end of the drill-shank. The drill is now properly located and the clamps N N' are closed firmly on it by screwing 110 up the clamping-screw P . I next turn the holder A^2 loosely on the drill till said holder is in the position shown in Figs. 2 and 4, and then tighten the screw B^2 until it firmly grips the inclosed drill. The rib r of the holder A^2 115 now lies on the horn n of the chuck S . I proceed to grind the drill in the same manner as described in my said pending application for Letters Patent. In the present device, however, I dispense with the link-connection 120 there shown, and substitute for it the beveled block L , on which the body-plate M slides as the end of the main bar R is raised or depressed. The block K is adjusted in the groove c of the head-piece J , Figs. 14, 15, as hereinbefore 125 described. The screw-bolt Z , by which the connecting-rod X is pivoted to the block K , forms a fixed center of oscillation, and when the main bar R is depressed the body-plate M , having the dovetailed channel, slides forward, 130 carrying with it its connected parts. This movement gives to the lips of the drill the eccentric or parabolic curving motion which is necessary in grinding the lips down to a

proper edge and clearance. The degree of such grinding is determined by the feed-screw V, turned by the disk p to the desired point on the rim of the disk in relation to the finger q. By this means one lip of the drill is ground, and it is necessary to grind the other lip correspondingly. For this purpose I withdraw the feed-screw V to its former position, elevate the end of the main bar R to swing the drill-point away from the wheel A, and then turn the holder A² over to the position shown in dotted lines in Fig. 2, bringing its rib r up on the horn n' of the chuck S. This movement turns the drill Q over one hundred and eighty degrees. I then proceed, as before, to grind that lip, and obtain the same curve and clearance by turning the feed-screw V again to the same point on the index of the disk p, as before. If, however, the drill to be ground is too small in diameter to be properly held in and presented by the clamps N N' to the wheel A, I use the supplemental drill-holder. (Shown in Figs. 7 to 13.) The insertion of the drill therein is fully illustrated by said figures, and in Figs. 12 and 13 is shown the manner in which such holder is inserted and held in the clamps N N'. It is so placed in said clamps that the pins c² of the handle b² lies against the end of the clamp N and serves as a stop. When this holder is used, the holder A² is dispensed with. To turn the drill one hundred and eighty degrees, the holder is withdrawn, turned half over, and inserted again in the clamps N N'; but the stop-pin c² now strikes against the clamp N.

The office of the lever C² is to support by its steps t t' a lug of the body-plate M, resting upon said steps. The lever is swung upon the screw s to engage or disengage at will the body-plate from either of said steps. By this means the machine can be left properly supported in either position.

I claim as a novel and useful invention and desire to secure by Letters Patent—

1. The combination of the head-piece J, having the groove e, the sliding block K, having the slot d, the screw e, the screw-bolt Z,

and the connecting-rod X of a drill-grinding attachment, substantially as described. 50

2. The drill-holder A² herein described, having a central aperture and a stem, a thumb-screw, B², passing longitudinally through said stem, and a rib, r, upon one side of said stem, in combination with the chuck-block S, having horns n and drill-stop m, and which is adjustable upon the main bar R of a drill-grinding machine, substantially as specified. 55

3. In a drill-grinding attachment, the combination of the grooved clamps N N', mounted and operated, substantially as described, and the guide D², having a spring-stem, u, as and for the purpose specified. 60

4. The combination of the head-piece J, having the groove e, and the beveled block L, the slotted sliding block K, the screws e f, the rod X, the nut and stud W, the main bar R, the feed-screw V, the disk p, the finger q, the feed-bracket U, the lugs o o', the channeled body-piece M, and means for drill-clamping, substantially as described. 65

5. The combination of the head-piece J, having the groove e, and the beveled block L, the slotted sliding block K, the screws e f, the rod X, the nut and stud W, the main bar R, and the channeled body-piece M, substantially as specified. 75

6. In a drill-grinding attachment, the lever C², having steps t t', and mounted by the screw-pivot s on the head-piece J, substantially as and for the purpose specified. 80

7. In a drill-grinding device, the combination of a head-piece, a main bar provided with drill-clamping, drill-feeding, and drill-turning mechanism, a block fixed to said head-piece, a body-piece channeled to receive said block, a connecting-rod pivoted at one end to the main bar in the plane thereof and vertically adjustable at its opposite end upon said head-piece, substantially as described, 85 and for the purpose specified. 90

FRANK MOSSBERG.
